(57) **ABSTRACT**

An engine cooling system is provided, which includes a water jacket through which coolant flows, a heat exchanger that cools the coolant, a bypass passage that bypasses the heat exchanger and recirculates the coolant to the water jacket, a first radiator passage that recirculates the coolant to the water jacket via the heat exchanger, a flow control device installed at a location where a coolant passage branches into the bypass passage and the first radiator passage, a second radiator passage that bypasses the flow control device and is connected to the first radiator passage, and a thermally-actuated valve installed in the second radiator passage. The flow control device performs a water flow control to adjust a coolant amount flowing into the water jacket by adjusting a coolant amount flowing through the bypass passage. The coolant flows into the first radiator passage through the second radiator passage, when the valve opens.

ENGINE COOLING SYSTEM

TECHNICAL FIELD

The disclosed technique relates to a cooling system for an engine, especially to a technique for controlling a temperature of a combustion chamber of the engine with high precision.

BACKGROUND OF THE DISCLOSURE

JP2016-128652A discloses a cooling device for an engine. This cooling device includes a radiator route 23 which circulates coolant between the engine and a radiator, and a radiator bypass route 24 which bypasses the radiator and circulates coolant.

The radiator bypass route 24 includes a first bypass route 25 in which apparatuses 31, 32 which are targets of heat exchange are installed, and a second bypass route 26 only with piping. The coolant which flowed through the radiator route 23 and the radiator bypass route 24 is returned to a water pump 21 through a return route 27.

A maximum flow rate of the second bypass route 26 is dramatically small compared with a maximum flow rate of each of the radiator route 23 and the first bypass route 25 (see FIG. 7 of JP2016-128652A).

The cooling device also includes a rotary flow control valve 50. The rotary flow control valve 50 controls a rotational position of a rotary valve body 51 according to a temperature of a fluid temperature sensor 77 installed in a circulation path 76 inside a housing. Thus, the flow of the coolant to the radiator route 23, the first bypass route 25, and the second bypass route 26 is controlled.

A combustion chamber becomes high temperature while the engine operates. In order to cool the combustion chamber, as also provided to the cooling device of JP2016-128652A, a passage through which the coolant cooled by the radiator flows (so-called "water jacket") is formed in a part of a cylinder bore, a cylinder head, etc. which constitute a main body of the engine, around the combustion chamber.

Meanwhile, in the engine combustion control, the temperature inside the combustion chamber (in-cylinder temperature) is one of important factors. More precise control of the in-cylinder temperature is required as the combustion control becomes more advanced. For example, in order to stably control the compression ignition combustion (CI combustion), it is necessary to more accurately control the in-cylinder temperature at a temperature higher than in the spark ignition combustion (SI combustion).

In the in-cylinder temperature control, a wall temperature of the combustion chamber is one of important factors. Like the conventional technique, only keeping the low temperature of the coolant which circulates in the water jacket in order to suppress an excessive temperature increase of the combustion chamber cannot realize the advanced combustion control. Rather, it is necessary to stably control the cooling by the coolant with a high response so that the wall temperature of the combustion chamber can be controlled.

In the cooling device of JP2016-128652A, the radiator bypass route is comprised of the first bypass route and the second bypass route. The first bypass route is long, where the apparatuses which are targets of heat exchange are installed. On the other hand, the second bypass route is short, and is comprised only of piping. However, the upper limit flow rate of the second bypass route is dramatically small compared with the upper limit flow rate of the first bypass route.

Therefore, when cooling while bypassing the radiator, most of the coolant flows into the first bypass route. An amount of coolant which flows into the second bypass route is small. Therefore, because of external causes such as environmental temperature, and influences of apparatuses, the temperature of the coolant which flows into the water jacket will not become stable. The amount of coolant which flows into the water jacket does not change much, either. Therefore, it is difficult to stably control the cooling by the coolant.

When cooling via the radiator, the path through which the coolant flows becomes even longer. Therefore, the response of the control is slow, and it is easy to be influenced by the environmental temperature, etc. Therefore, also in this case, it is difficult to stably control the cooling by the coolant with high response.

SUMMARY OF THE DISCLOSURE

Thus, the disclosed technique aims at stably controlling cooling of a water jacket by coolant with a high response. Therefore, an advanced combustion control, such as CI combustion, can be realized.

According to one aspect of the present disclosure, a cooling system for an engine is provided, which includes a water jacket formed in a cylinder head of the engine and through which coolant flows, a heat exchanger that cools the coolant, a bypass passage that bypasses the heat exchanger and recirculates the coolant to the water jacket, a first radiator passage that recirculates the coolant to the water jacket via the heat exchanger, a flow control device installed at a location where a passage of the coolant branches into the bypass passage and the first radiator passage, a second radiator passage that bypasses the flow control device and is connected to the first radiator passage, and a thermally-actuated valve installed in the second radiator passage.

The flow control device performs a water flow control to adjust an amount of coolant flowing into the water jacket by adjusting an amount of coolant flowing through the bypass passage.

Further, by the thermally-actuated valve opening, the coolant is recirculated to the water jacket through the second radiator passage and the first radiator passage.

The bypass passage that bypasses the heat exchanger and the first radiator passage that passes the heat exchanger are provided in this engine cooling system. According to this configuration, the coolant flowing through the first radiator passage is cooled by the heat exchanger, but the coolant flowing through the bypass passage is not cooled by the heat exchanger.

Further, the flow control device installed at the branched part of the bypass passage and the first radiator passage, performs the water flow control to adjust the amount of coolant flowing in the water jacket formed in the cylinder head of the engine (i.e., the periphery of a combustion chamber), through the bypass passage.

That is, when the water flow control is performed, the amount of coolant which circulates in the water jacket without being cooled by the heat exchanger is adjusted. In detail, if the amount of coolant which flows in the water jacket decreases, the heat transfer coefficient between the water jacket and the combustion chamber also decreases accordingly. If the amount of coolant which flows in the water jacket increases, the heat transfer coefficient between the water jacket and the combustion chamber also increases accordingly.

By this water flow control, the heat transfer coefficient between the water jacket and the combustion chamber can be adjusted, and as a result, a wall temperature of the combustion chamber can be held constant.

In addition, in this cooling system, the second radiator passage that bypasses the flow control device and is connected to the first radiator passage is provided. Further, the thermally-actuated valve is provided to the second radiator passage. When the thermally-actuated valve opens, the coolant flows through the second radiator passage and flows into the first radiator passage.

The thermally-actuated valve opens and closes at a given high temperature set beforehand. Thus, if the temperature of the coolant flowing in the water jacket becomes excessively high, the coolant can be flowed into the first radiator passage independently of the flow control device. Since the coolant flowed into the first radiator passage is cooled, the temperature of the coolant which is circulated in the water jacket can be reduced. As a result, while setting the temperature of the circulating coolant high, it can suppress the coolant temperature from becoming excessively high.

By the combination of the water flow control using the bypass passage and the high temperature control using the thermally-actuated valve, the cooling of the water jacket with the coolant can be stably controlled with high response. As a result, the advanced combustion control can be achieved as well as improving fuel efficiency.

Furthermore, the thermally-actuated valve is installed at a part of bypassing the flow control device. Therefore, even if the abnormality occurs in the flow control device and the coolant temperature rises, when the temperature becomes above a given temperature, the thermally-actuated valve opens to cool the coolant by the heat exchanger. It can suppress the overheat of the engine.

In the cooling system, the flow control device may perform a water temperature control to adjust a temperature of the coolant which flows into the water jacket by adjusting an amount of coolant flowing through the first radiator passage.

That is, when the water temperature control is performed, among the coolant which circulates in the water jacket, the amount of coolant to be cooled by the heat exchanger is adjusted. Thus, even if the amount of coolant flowing in the water jacket is constant (i.e., not performing the water flow control), a heat exchanging quantity with the combustion chamber can be changed.

Therefore, by combining the water flow control with the water temperature control, a range where the temperature of the coolant flowing in the water jacket can be stabilized can be expanded. As a result, the advanced combustion control can be achieved in the wide range, which further improves fuel efficiency.

In the cooling system, the flow control device may include a housing provided with an inflow opening through which the coolant inflows, and the bypass passage and the first radiator passage, a rotary valve body rotatably accommodated in the housing, intervening between the inflow opening and each of the bypass passage and the first radiator passage, and allowing the coolant flowed into the inflow opening by passing through a first water flow opening and a second water flow opening to flow into each of the bypass passage and the first radiator passage, and an actuator that rotates the rotary valve body. Amounts of coolant flowing through the bypass passage and the first radiator passage may be adjusted by controlling the actuator and changing openings of the first water flow opening and the second water flow opening, respectively.

According to this configuration, by the control of the actuator of the flow control device, the rotary valve body where the two water flow openings are formed rotates. By the rotary valve body being rotated, the opening between the inflow opening and each of the bypass passage and the first radiator passage is changed so that the amounts of the coolant flowing through the bypass passage and the first radiator passage is adjusted.

Therefore, only by the actuator rotating the rotary valve body, the amounts of the coolant flowing through each of the bypass passage and the first radiator passage can be adjusted. For example, the amount of the coolant flowing through each of the bypass passage and the first radiator passage can be set to zero, the amount of the coolant flowing through the bypass passage or the first radiator passage can be set to zero, or the amounts of the coolant flowing through each of the bypass passage and the first radiator passage can be changed. Since this is achieved only by the actuator rotating the rotary valve body, the coolant amount can easily be performed precisely.

The flow control device may include a first electromagnetic valve and a second electromagnetic valve that open and close passages of the coolant. Amounts of coolant flowing through the bypass passage and the first radiator passage may be adjusted by controlling the first electromagnetic valve and the second electromagnetic valve, respectively.

That is, in this cooling system, the flow control device is comprised of the two electromagnetic valves. For example, when changing the state between flowing or not flowing the coolant to each of the bypass passage and the first radiator passage, each of the first electromagnetic valve and the second electromagnetic valve can be opened or closed accordingly. When adjusting the amounts of the coolant flowing through each of the bypass passage and the first radiator passage, the open and close timings of the valve may be adjusted according to the target amounts.

According to this cooling system, since the flow control device is comprised of the two electromagnetic valves, the system configuration can be compact.

The temperature of the coolant flowing through the water jacket when the water flow control is performed and the water temperature control is not performed may be set higher than the temperature of the coolant flowing through the water jacket when the water temperature control is performed and the water flow control is not performed.

According to this cooling system, by combining the water flow control and the water temperature control, the range where the temperature of the coolant flowing in the water jacket can be stabilized can be expanded. Further, the temperature of the coolant flowing in the water jacket is set relatively higher when the water flow control is performed and the water temperature control is not performed, whereas is set relatively lower when the water temperature control is performed and the water flow control is not performed.

In the water temperature control, the heat exchanging quantity is adjusted by the coolant cooled by the heat exchanger. On the other hand, in the water flow control, the heat transfer coefficient is adjusted by changing the amount of the coolant circulating while bypassing the heat exchanger. Therefore, since the water flow control excels the water temperature control in the response and stability, the water flow control can stably control the cooling of the water jacket with the coolant even if it is set to a high temperature.

In this manner, the precise control of the coolant at the high temperature becomes possible, and the advanced combustion control can be performed stably while expanding the range.

BRIEF DESCRIPTION OF DRAWINGS

FIG. 1 is a schematic view illustrating a cooling system for an engine.

FIG. 2 is a schematic view illustrating an internal structure of an upper part of an engine body.

FIG. 3 is a schematic view illustrating a structure of a coolant control valve, where an upper figure is a longitudinal cross section of the coolant control valve, and a lower figure is a transverse cross section when seen in a direction indicated by an arrow of the upper figure.

FIG. 4 is a graph illustrating an open-and-close operation of a thermally-actuated valve.

FIG. 5 illustrates a table where how the coolant flows is summarized.

FIG. 6 is a view illustrating a flowing state in the cooling system corresponding to the table of FIG. 5.

FIG. 7 is a view illustrating how the coolant flows during full warm-up.

FIG. 8 is a schematic view illustrating a modification of the cooling system for the engine.

DETAILED DESCRIPTION OF DISCLOSURE

Hereinafter, the disclosed technique is described. Note that the following description is merely illustration.

<Configuration of Cooling System>

FIG. 1 illustrates a cooling system for an engine, which is constructed based on the disclosed technique. A cooling system 2 is mounted on an automobile (vehicle). The automobile travels by a driving force of the engine. Note that, although the automobile may be a hybrid vehicle carrying an engine and a motor, the automobile is a vehicle only carrying an engine in the following description.

(Engine, Auxiliary Machines)

The disclosed technique is applicable to both a gasoline engine and a diesel engine. However, from the viewpoint of the advanced combustion control, the gasoline engine is preferred. Therefore, an engine 1 is the gasoline engine in this embodiment.

The engine 1 has an engine body 10 which is elongated in an extending direction of a driving shaft (not illustrated). FIG. 2 illustrates a simplified internal structure of an upper part of the engine body 10. The engine body 10 is comprised of a cylinder block 10B, and a cylinder head 10H assembled to an upper part of the cylinder block 10B. A plurality of cylinders (cylinders 11) lined up in series along the driving shaft are provided inside the engine body 10.

That is, a plurality of cylindrical cylinders 11 are formed in the cylinder block 10B. A piston 12 is slidably accommodated in each cylinder 11. A combustion chamber 13 is formed by partitioning each cylinder 11 with an upper surface of the piston 12, and a lower surface of the cylinder head 10H which covers an upper part of the cylinder 11.

In the lower surface of the cylinder head 10H which constitutes an upper surface of the combustion chamber 13, two exhaust openings 14 which are opened and closed by exhaust valves 14a, and two intake openings 16 which are opened and closed by intake valves 16a. Each exhaust opening 14 is connected with an exhaust device (outside the drawing) through an exhaust port 15. Each intake opening 16 is connected with an intake device (outside the drawing)

through an intake port 17. In this engine 1, a spark plug 18 and a fuel injection valve 19 are attached between the exhaust openings 14 and the intake openings 16.

The engine 1 can inject gasoline into the combustion chamber 13 from the fuel injection valve 19. The engine 1 can ignite an air-fuel mixture which is formed inside the combustion chamber 13 by the spark plug 18 to combust the air-fuel mixture (so-called "spark ignition (SI) combustion"). Further, this engine 1 is designed so that a compression ratio (geometric compression ratio) is higher than engines which only perform SI combustion. The engine 1 is constructed so that it can also perform combustion by compression ignition (so-called "CI combustion").

A water jacket 20 through which cooling water (coolant) flows is formed inside the engine body 10. The water jacket 20 constitutes a part of a passage provided to the cooling system 2. The water jacket 20 has an in-block jacket 21, and an in-head jacket 22. The in-block jacket 21 is formed in the cylinder block 10B so that it spreads along the outer circumference of each cylinder.

The in-head jacket 22 is formed in the cylinder head 10H so that it communicates with the in-block jacket 21. The in-head jacket 22 has a first jacket 22a (an example of a "water jacket" in the disclosed technique), and a second jacket 22b. The first jacket 22a and the second jacket 22b constitute mutually independent passages.

The first jacket 22a is formed so that it extends along an upper part of each cylinder 11 (i.e., along the perimeter of the combustion chamber 13). Therefore, the coolant which flows through the first jacket 22a mainly exchanges heat with (mainly, cools) the combustion chamber 13 where combustion takes place.

In detail, the coolant which flows through the first jacket 22a exchanges heat with atmosphere inside the combustion chamber 13 via the wall surface of the combustion chamber 13. That is, a wall temperature of the combustion chamber 13 is cooled by the coolant which flows through the first jacket 22a. Therefore, in order to stably control the wall temperature of the combustion chamber 13, controlling the cooling by the coolant which flows through the first jacket 22a highly-accurately and with a high response becomes important.

On the other hand, the second jacket 22b is formed so that it extends along a circumference part of the exhaust port 15 of each cylinder 11. The coolant which flows through the second jacket 22b mainly exchanges heat with (mainly, cools) the exhaust port 15 through which hot exhaust gas flows.

As illustrated in FIGS. 1 and 2, a water pump 3 is installed in the cylinder block 10B, at an end part (inflow-side end part 10a) of the engine body 10. The water pump 3 constitutes a part of the cooling system 2.

The water pump 3 is a mechanical pump in which a rotation shaft of a pump is coupled to a driving shaft of the engine 1 via a belt-pulley mechanism, etc. The water pump 3 operates by the driving force of the engine 1. Note that the water pump 3 may be an electric pump which can operate independently from the engine 1.

The in-block jacket 21 is connected with a discharge port 3a of the water pump 3 via a coolant introducing passage 23. Therefore, the coolant discharged from the water pump 3 flows into the in-block jacket 21 through the coolant introducing passage 23. The coolant which flowed into the in-block jacket 21 flows into the in-head jacket 22. In detail, it dividedly flows into the first jacket 22a and the second jacket 22b.

As illustrated in FIGS. 1 and 2, a coolant control valve 4 (CCV; an example of a “flow control device” in the disclosed technique) and a thermally-actuated valve 54 are installed in the cylinder head 10H, at an end part (outflow-side end part 10b) opposite from the inflow-side end part 10a of the engine body 10. The coolant control valve 4 and the thermally-actuated valve 54 constitute a part of the cooling system 2.

A pair of first coolant deriving passages 24 which communicate with the first jacket 22a are formed in the outflow-side end part 10b of the cylinder head 10H. One of the first coolant deriving passages 24 (a CCV-side first coolant deriving passage 24) is connected to the coolant control valve 4. The other first coolant deriving passage 24 (a thermostat-side first coolant deriving passage 24) is connected to a second radiator passage 52 via the thermally-actuated valve 54.

Therefore, the coolant which flows through the first jacket 22a flows out of the engine body 10 through the CCV-side first coolant deriving passage 24, and flows into the coolant control valve 4. Then, when the thermally-actuated valve 54 is open, the coolant flows out of the engine body 10 through the thermostat-side first coolant deriving passage 24, and flows into the second radiator passage 52. Details of the thermally-actuated valve 54 and the coolant control valve 4 will be described later.

A second coolant deriving passage 25 which communicates with the second jacket 22b is formed at a location of the outflow-side end part 10b on the exhaust side of the cylinder head 10H. Therefore, the coolant which flows through the second jacket 22b flows out of the engine body 10 through the second coolant deriving passage 25, and flows into a second circulation passage 31 (described later).

A third coolant deriving passage 26 which communicates with the in-block jacket 21 is formed at a location of the outflow-side end part 10b on the intake side of the cylinder block 10B. Therefore, part of the coolant which flows through the in-block jacket 21 flows out of the engine body 10 through the third coolant deriving passage 26, and flows into a third circulation passage 41 (described later).

Various auxiliary machines built into the cooling system 2 are mounted on the automobile in addition to the engine 1. In this automobile, an exhaust gas recirculation (EGR) cooler 5, an EGR valve 6, a heater 7, an oil cooler 8, and an automatic transmission fluid (ATF) heat exchanger 9 are mounted as such auxiliary machines.

Although not illustrated, an EGR system is additionally provided to the engine 1. The EGR cooler 5 and the EGR valve 6 are installed in the EGR system. The heater 7 is built into an air conditioner which adjusts air inside a vehicle cabin.

The oil cooler 8 is installed in a system which circulates lubricating oil and supplies it to the engine 1. The ATF heat exchanger 9 is installed in a system which circulates hydraulic fluid and supplies it to the automatic transmission. In this cooling system 2 of the engine 1, it also exchanges heat with these auxiliary machines, as well as the engine 1.

(Cooling System)

The structure and layout are devised for the cooling system 2 so that the advanced combustion control like Homogeneous Charge Compression Ignition combustion (so-called “HCCI combustion”) can be performed by the engine 1.

In detail, as illustrated in FIG. 1, the cooling system 2 is provided with, in addition to the water pump 3, the coolant control valve 4, and the thermally-actuated valve 54 which are described above, a radiator 27 (an example of a “heat

exchanger” in the disclosed technique). Roughly, the cooling system 2 is provided with, as passages through which the coolant circulates, a second circuit 30, a third circuit 40, and a first circuit 50.

5 (Second Circuit)

The second circuit 30 has the second circulation passage 31 where a passage which is branched into two (a first branch passage 31a and a second branch passage 31b) is provided. In the first branch passage 31a, the EGR cooler 5 and the heater 7 are disposed. The EGR valve 6 is disposed in the second branch passage 31b. An upstream end of the second circulation passage 31 is connected to the second coolant deriving passage 25. A downstream end of the second circulation passage 31 is connected to a suction port 3b of the water pump 3 in a state where it is joined to the first circuit 50 and the third circuit 40.

Inside the engine body 10, the in-block jacket 21, the second jacket 22b, and the second coolant deriving passage 25 constitute a passage of the second circuit 30. Therefore, 10 in the second circuit 30, among the coolant discharged from the water pump 3, coolant which flowed through the in-block jacket 21 and the second jacket 22b is divided and flows into each of the first branch passage 31a and the second branch passage 31b. After being joined, it returns to 15 the water pump 3.

The coolant which flows through the second circuit 30 exchanges heat with the engine 1 (mainly, with the exhaust port 15). Further, it also exchanges heat with the EGR cooler 5, the heater 7, and the EGR valve 6.

30 (Third Circuit)

The third circuit 40 has the third circulation passage 41 where the oil cooler 8 and the ATF heat exchanger 9 are installed. An upstream end of the third circulation passage 41 is connected to the third coolant deriving passage 26. A 35 downstream end of the third circulation passage 41 is connected to the suction port 3b of the water pump 3 in a state where it is joined to the first circuit 50 and the second circuit 30.

Inside the engine body 10, the in-block jacket 21 and the 40 third coolant deriving passage 26 constitute a passage of the third circuit 40. Therefore, in the third circuit 40, among the coolant discharged from the water pump 3, part of the coolant which flows through the in-block jacket 21 flows into the third circulation passage 41 and returns to the water 45 pump 3. The coolant which flows through the third circuit 40 exchanges heat with the oil cooler 8 and the ATF heat exchanger 9.

(First Circuit)

The first circuit 50 has a bypass passage 53, a first radiator 50 passage 51, and the second radiator passage 52. Inside the engine body 10, the in-block jacket 21, the first jacket 22a, and the pair of first coolant deriving passages 24 constitute a passage of the first circuit 50.

As described above, inside the engine body, the passage 55 of the first circuit 50 branches into the two first coolant deriving passages 24, where one of them, the CCV-side first coolant deriving passage 24 is connected to the coolant control valve 4, and the other, the thermostat-side first coolant deriving passage 24 is connected to the second radiator passage 52 via the thermally-actuated valve 54.

The passage which goes through the CCV-side first coolant deriving passage 24 branches into the bypass passage 53 and the first radiator passage 51 in the coolant control valve 4. A downstream end of each of the bypass passage 53 and 60 the first radiator passage 51 is connected to the suction port 3b of the water pump 3 in a state where it is joined to the second circuit 30 and the third circuit 40.

The radiator 27 is provided to the first radiator passage 51. The radiator 27 is installed rearward of a front grille of the automobile. The coolant which flows through the radiator 27 mainly exchanges heat with outside air caused by the vehicle traveling. The coolant radiates heat while flowing through the first radiator passage 51 so that it is cooled.

Therefore, the first radiator passage 51 cools, by the radiator 27, the coolant which is discharged from the water pump 3 and is heated by the heat exchange while the coolant flows through the in-block jacket 21 and the first jacket 22a, and recirculates it to the in-block jacket 21 and the first jacket 22a.

The bypass passage 53 is a passage which bypasses the first radiator passage 51. The bypass passage 53 is shorter than the first radiator passage 51, and is comprised only of piping.

Thus, the bypass passage 53 recirculates, to the in-block jacket 21 and the first jacket 22a, the coolant which is discharged from the water pump 3 and exchanges heat while flowing through the in-block jacket 21 and the first jacket 22a in a state almost as it is, without cooling by the radiator 27.

The passage which goes through the thermostat-side first coolant deriving passage 24 is connected to an upstream end of the second radiator passage 52. The thermally-actuated valve 54 is installed in the end of the second radiator passage 52. A downstream end of the second radiator passage 52 is connected to a part of the first radiator passage 51 upstream of the radiator 27. In other words, the second radiator passage 52 bypasses the coolant control valve 4, and is connected to the first radiator passage 51. Note that the thermally-actuated valve 54 may be installed at parts other than the end of the second radiator passage 52.

The thermally-actuated valve 54 is a known device which opens and closes at a high temperature set beforehand. The thermally-actuated valve 54 has a valve body which is biased in a closing direction by an elastic force of a spring. The valve body is displaced according to action of wax to open and close the thermally-actuated valve 54.

When the thermally-actuated valve 54 closes, the thermostat-side first coolant deriving passage 24 does not communicate with the second radiator passage 52 (the coolant does not flow). When the thermally-actuated valve 54 opens, the thermostat-side first coolant deriving passage 24 communicates with the first radiator passage 51 via the second radiator passage 52. Therefore, when the thermally-actuated valve 54 opens, the coolant which flows through the first jacket 22a passes through the second radiator passage 52, and flows into the first radiator passage 51.

FIG. 4 illustrates open-and-close operation of the thermally-actuated valve 54. The thermally-actuated valve 54 fully opens when the temperature of the coolant which flows through the thermally-actuated valve 54 becomes above a given temperature (a fully-open temperature to, for example, 100°C.).

On the other hand, when the temperature of the coolant which flows through the thermally-actuated valve 54 becomes below the fully-open temperature to, the valve body is gradually displaced in a closing direction by the elastic force action of the spring caused by contraction of wax. The thermally-actuated valve 54 gradually closes. When the temperature of the coolant which flows through the thermally-actuated valve 54 becomes below the given temperature (a fully-closed temperature t_c , for example, about 95°C.), the thermally-actuated valve 54 becomes fully closed. The thermally-actuated valve 54 automatically opens

and closes according to the temperature of the coolant which flows through the thermally-actuated valve 54. (Coolant Control Valve)

FIG. 3 illustrates the coolant control valve 4. The coolant control valve 4 is a valve which can adjust a flow rate of the coolant, and is comprised of a housing 60, a rotary valve body 61, and an actuator 62.

A cylindrical branching chamber 60a is provided inside the housing 60. The cylindrical rotary valve body 61 is 10 rotatably accommodated in the branching chamber 60a. In the housing 60, a first passage 63 and a second passage 64 are formed so that they extend radially outward from a given position in the outer circumference of the branching chamber 60a. The housing 60 is also provided with the bypass passage 53 and the first radiator passage 51. The first passage 63 is connected to the bypass passage 53. The second passage 64 is connected to the first radiator passage 51.

The branching chamber 60a opens at one end thereof. 20 This opening constitutes an inflow opening 65 through which the coolant flows into the branching chamber 60a. The housing 60 is attached to the cylinder head 10H so that the inflow opening 65 is coaxially connected to the CCV-side first coolant deriving passage 24. Therefore, a circumferential wall of the rotary valve body 61 intervenes between the inflow opening 65 and each of the first passage 63 and the bypass passage 53, and the second passage 64, and the first radiator passage 51.

A first water flow opening 61a and a second water flow 30 opening 61b are formed at a given position of the circumferential wall of the rotary valve body 61. The first water flow opening 61a is longer in length in the circumferential direction than the second water flow opening 61b, and has a relatively large opening area. Depending on the rotational 35 position of the rotary valve body 61, the inflow opening 65 communicates or does not communicate with each of the first passage 63 and the second passage 64 via each of the first water flow opening 61a and the second water flow opening 61b. Further, while communicating, an opening 40 between each of the first passage 63 and the second passage 64 and the inflow opening 65 varies according to the rotational position of the rotary valve body 61.

The other end of the branching chamber 60a is sealed with a closure wall 66. The actuator 62 is accommodated inside 45 the housing 60, at the opposite side of the branching chamber 60a with respect to the closure wall 66. A rotation shaft 62a of the actuator 62 projects into the branching chamber 60a through a shaft hole which opens at the center of the closure wall 66. The rotary valve body 61 is attached 50 via support arms 62b to the rotation shaft 62a projected into the branching chamber 60a. The rotary valve body 61 rotates by controlling the actuator 62.

As illustrated in FIG. 1, in the cooling system 2, an inlet water temperature sensor S1 and an in-jacket water temperature sensor S2 are installed. The inlet water temperature sensor S1 is disposed in a passage where the first circuit 50, the second circuit 30, and the third circuit 40 join and flow into the water pump 3. The in-jacket water temperature sensor S2 is disposed at the first jacket 22a. The inlet water temperature sensor S1 measures a temperature of the entire coolant which circulates the cooling system 2. The in-jacket water temperature sensor S2 measures a temperature of the coolant which flows through the first jacket 22a.

These sensors S1 and S2 are used for a coolant control and 65 a combustion control. For example, when performing the advanced combustion control, the in-jacket water temperature sensor S2 is used for estimating the wall temperature of

11

the combustion chamber 13. The in-jacket water temperature sensor S2 is also used for controlling the actuator 62.

This cooling system 2 controls the coolant control valve 4 based on the measurement of the in-jacket water temperature sensor S2. This adjusts an amount of coolant which flows into the first circuit 50 (i.e., the bypass passage 53 and the first radiator passage 51). Note that a flow of the coolant in the second radiator passage 52 is automatically adjusted by the thermally-actuated valve 54.

The coolant which flows through the cooling system 2 is mainly cooled by the radiator 27 installed in the first radiator passage 51. Therefore, the temperature of the coolant which flows into the cooling system 2 is adjusted.

That is, the main constituent of the cooling system 2 is the first circuit 50. The flow rate and the temperature of the coolant in each of the second circuit 30 and the third circuit 40 change according to the adjustment of the flow rate and the temperature of the coolant in the first circuit 50. In this cooling system 2, although the first circuit 50 is essential, the second circuit 30 and the third circuit 40 are not essential.

<How Coolant Flows>

As described above, the coolant which flows through the first jacket 22a mainly exchanges heat with the combustion chamber 13 to cool the wall temperature of the combustion chamber 13. In this cooling system 2, in order to perform the combustion control of the engine 1 stably and efficiently, a plurality of ways of the coolant to flow are set according to the temperature of the coolant which flows through the first jacket 22a (the measurement of the in-jacket water temperature sensor S2).

FIG. 5 illustrates a table where the water flow patterns are summarized. An upper row of the table illustrates the temperature state of the combustion chamber 13. A middle row of the table illustrates the flowing state of the first circuit 50 according to the temperature state. A lower row of the table illustrates the state of the coolant control valve 4 according to the temperature state. Further, FIG. 6 illustrates the flowing state of each circuit in the cooling system 2 corresponding to the table of FIG. 5.

In the coolant control valve 4, the actuator 62 is controlled so that the amounts of coolant which flows into both the first passage 63 and the second passage 64 are adjusted. That is, the opening of each of the first water flow opening 61a and the second water flow opening 61b is changed so that the rotary valve body 61 becomes at a given rotational position.

“Low Temperature” is in a state of a so-called “cold start,” such as immediately after a startup of the engine 1. “Low Temperature” is a state where the temperature of the coolant which flows through the first jacket 22a (first change temperature) is below 40° C., for example. “Full Warm-up” is in a state where the engine 1 becomes warm at a temperature suitable for the operation of the engine 1, and is a so-called warm state.

“Full Warm-up” is a state where the temperature of the coolant which flows through the first jacket 22a (second change temperature) is above 80° C., for example. “Warm-up” is a state between “Low Temperature” and “Full Warm-up” (i.e., a transition stage). “Warm-up” is a state where the temperature of the coolant which flows through the first jacket 22a is 40° C. to 80° C., for example (above the first change temperature and below the second change temperature).

FIG. 6 illustrates in a left figure a state of the cooling system during “Low Temperature.” The temperature of the coolant is lower than the fully-closed temperature tc. Therefore, the thermally-actuated valve 54 is fully closed. The

12

coolant will not pass through the second radiator passage 52 and flow into the first radiator passage 51.

At the coolant control valve 4, the coolant neither flows into the first radiator passage 51 nor the bypass passage 53 (a flow rate of both the passages is zero). That is, the circulation of the coolant is not performed in the first circuit 50. At this time, the coolant control valve 4 is set so that the rotary valve body 61 is at a rotational position where both the first passage 63 and the second passage 64 do not communicate with the inflow opening 65.

Since the coolant does not flow into the first radiator passage 51, the coolant will not be cooled by the radiator 27. Therefore, the coolant promptly increases in the temperature. In addition, the combustion chamber 13 will not be cooled by the circulation of the coolant. The combustion chamber 13 can be promptly heated by combustion heat. Since the engine 1 promptly starts to the temperature state suitable for combustion, fuel efficiency can be improved. At this time, the coolant discharged from the water pump 3 circulates through the second circuit 30 and the third circuit 40.

FIG. 6 illustrates in a center figure a state of the cooling system during “Warm-up.” Also during “Warm-up,” the temperature of the coolant is lower than the fully-closed temperature tc. Therefore, the thermally-actuated valve 54 is fully closed. The coolant will not pass through the second radiator passage 52, and flow into the first radiator passage 51.

On the contrary, although the coolant control valve 4 does not allow the coolant to flow into the first radiator passage 51 during “Warm-up” (the flow rate of the first radiator passage 51 is zero), it allows the coolant to flow into the bypass passage 53. That is, in the first circuit 50, the coolant circulates only through the bypass passage 53. At this time, the coolant control valve 4 is set so that the rotary valve body 61 is at a rotational position where only the first passage 63 communicates with the inflow opening 65. An opening between the first passage 63 and the inflow opening 65 is fully open.

Since the coolant does not flow into the first radiator passage 51, the coolant promptly increases in the temperature. On the other hand, since the coolant flows into the bypass passage 53, the coolant flows into the first jacket 22a. The bypass passage 53 is short. Further, since the coolant control valve 4 is set to be fully opened, most of the coolant flows through the bypass passage 53 and the first jacket 22a.

The combustion chamber 13 can be promptly heated by the circulating coolant. Since the coolant circulates, the combustion chamber 13 and its circumference can be heated uniformly. Since the engine 1 promptly starts to the temperature state suitable for combustion, fuel efficiency can be improved. Note that, at this time, the remainder of the coolant discharged from the water pump 3 circulates through the second circuit 30 and the third circuit 40 (also similar during “Full Warm-up”).

FIG. 6 illustrates in a right figure a state of the cooling system during “Full Warm-up.” During “Full Warm-up,” the engine 1 reaches the temperature state suitable for combustion.

Therefore, as the load of the engine 1 changes, the temperature of the coolant which flows through the first jacket 22a can become above 100° C. and can become below 95° C. Therefore, in “Full Warm-up,” the thermally-actuated valve 54 opens and closes.

When the load of the engine 1 increases and the combustion chamber 13 becomes high in the temperature, the combustion chamber 13 needs to be cooled in order to keep

the engine 1 at the temperature state suitable for combustion. Thus, during "Full Warm-up," the circulation of the coolant is performed using the entire first circuit 50.

For example, the coolant flows into both the bypass passage 53 and the first radiator passage 51. In that case, the coolant control valve 4 is set so that the rotary valve body 61 is at a rotational position where both the first passage 63 and the second passage 64 communicate with the inflow opening 65. During "Full Warm-up," the flow rate of the coolant is adjusted in both the first passage 63 (bypass passage 53) and the second passage 64 (first radiator passage 51) according to the load of the engine 1.

That is, in order to enable the advanced combustion control like HCCI combustion, the water flow control and the water temperature control of the coolant which flows into the first jacket 22a are performed according to the load of the engine 1. Therefore, the wall temperature of the combustion chamber 13 can be accurately held at the given high temperature.

(How Coolant Flows During Full Warm-Up)

FIG. 7 illustrates one concrete example of how the coolant flows during Full Warm-up. FIG. 7 illustrates changes in main parameters according to the load of the engine 1 respectively in charts (A) to (D).

Chart (A) illustrates a change G1 in the total amount of the coolant which passes through the coolant control valve 4, and a change G2 in the amount of coolant which passes through the first radiator passage 51. Chart (B) illustrates details of the change in the amount of coolant which flows through the first circuit 50 (that is, a change G3 in the amount of coolant which flows into the bypass passage 53 from the coolant control valve 4, a change G4 in the amount of coolant which flows through the second radiator passage 52, and a change G5 in the amount of coolant which flows into the first radiator passage 51 from the coolant control valve 4.)

Chart (C) illustrates a change G6 in the temperature of the coolant which flows through the first jacket 22a, and a change G7 in the temperature of the coolant which flows into the water pump 3. In other words, changes in the measurements of the in jacket water temperature sensor S2 and the inlet water temperature sensor S1 are illustrated. Chart (D) illustrates a change G8 in the wall temperature of the combustion chamber 13.

The load range of the engine 1 is divided into three ranges, in association with the control of the coolant, which is comprised of a range below a first load L1 (low-load range), a range above a second load L2 (high-load range), and a range above the first load L1 and below the second load L2 (middle-load range). The first load L1 and the second load L2 are values which are defined according to conditions, such as specifications of the engine 1 and the cooling system 2, and the ambient temperature.

In this cooling system 2, the water flow control is performed in the low-load range, and the water temperature control is performed in the middle-load range. Therefore, in the low-load range and the middle-load range of the engine 1, the advanced combustion control like HCCI combustion can be performed.

That is, in order to realize such an advanced combustion control, it is necessary to accurately control the temperature inside the combustion chamber 13 (in-cylinder temperature) at the temperature higher than the common spark ignition combustion (SI combustion). On the other hand, since combustion heat decreases when the load of the engine 1 becomes smaller, the wall temperature of the combustion chamber 13 is required to be increased in order to maintain

the suitable in-cylinder temperature. On the other hand, since the combustion heat increases when the load of the engine 1 becomes larger, the wall temperature of the combustion chamber 13 is required to be decreased.

5 In order to accurately realize both the demands, it is required that a heat exchanging quantity (cooling quantity) by the coolant which flows through the first jacket 22a is stably controlled with high response. On the other hand, conventionally, the cooling quantity by the coolant which 10 flows through the first jacket 22a is controlled by cooling the coolant by the radiator 27 and controlling the temperature of the coolant.

However, since the calorific capacity of coolant is large, it needs a long period of time for raising and lowering the 15 temperature of the coolant. Therefore, the required response cannot be acquired by this method of controlling the temperature of the coolant. In addition, the influence of the external causes, such as the environmental temperature, is also great. Therefore, the realization of the stable control is 20 difficult only by this method. On the other hand, the flow rate of the coolant can be fluctuated in a short period of time. The heat transfer coefficient can be adjusted with high response. Thus, in this cooling system 2, by performing not only the water temperature control of the coolant but also performing the water flow control of the coolant, the cooling by the coolant which flows through the first jacket 22a can be stably controlled with high response.

In detail, the amount of coolant which flows through the 25 first passage 63 is controlled using the coolant control valve 4. Therefore, the amount of coolant which flows through the first jacket 22a is changed to adjust the heat transfer coefficient between the first jacket 22a and the combustion chamber 13.

(Low-Load Range)

30 As illustrated in FIG. 7, in the low-load range, the coolant control valve 4 adjusts the amount of coolant which flows through the bypass passage 53, without the coolant flowing through the first radiator passage 51 (see G3, G5). In detail, in the low-load range, the coolant control valve 4 adjusts the 35 amount of coolant so that it reduces the amount of coolant which flows through the bypass passage 53 as the load of the engine 1 decreases.

At this time, the coolant control valve 4 controls the 40 actuator 62 so that the rotary valve body 61 is located at a rotational position where the inflow opening 65 does not communicate with the second passage 64, and the inflow opening 65 communicates with the first passage 63. Then, the opening between the inflow opening 65 and the first 45 passage 63 is adjusted according to the load of the engine 1.

The coolant which flows out of the coolant control valve 4 flows into the bypass passage 53 and circulates between the first radiator passage 51 and the first jacket 22a, without 50 flowing into the first radiator passage 51. Unless the coolant flows into the first radiator passage 51, the coolant will not be cooled by the radiator 27. The coolant flows into the first 55 radiator passage 51 only when the thermally-actuated valve 54 opens, and the coolant flows into the second radiator passage 52.

That is, the temperature of the coolant in the low-load 60 range is determined by the thermally-actuated valve 54. On the other hand, the temperature at which the thermally-actuated valve 54 opens and closes is set at a comparatively high temperature. Therefore, the temperature of the coolant which flows through the first jacket 22a becomes high. By 65 setting the temperature of the coolant high, it becomes possible to maintain the wall temperature of the combustion chamber 13 at the comparatively high temperature (that is,

a target temperature tw). Note that, in the low-load range, since the coolant hardly flows into the first radiator passage **51**, the temperature of the entire coolant rises gradually as the load of the engine **1** increases (see G7).

If the amount of coolant which flows through the bypass passage **53** (i.e., the first jacket **22a**) decreases, the heat transfer coefficient between the first jacket **22a** and the combustion chamber **13** also decreases accordingly. Therefore, even if the load decreases and the combustion heat decreases, the wall temperature of the combustion chamber **13** can be adjusted higher because the amount of coolant decreases accordingly. If the amount of coolant which flows through the first jacket **22a** increases, the heat transfer coefficient between the first jacket **22a** and the combustion chamber **13** also increases accordingly. Therefore, even if the load increases and the combustion heat increases, the wall temperature of the combustion chamber **13** can be adjusted low because the amount of coolant increases accordingly.

As the result, the wall temperature of the combustion chamber **13** can be held constant (see G8).

Further, in this engine **1**, in order to enable the advanced combustion control, the target wall temperature tw of the combustion chamber **13** is set higher than conventional techniques. Accordingly, a first target water temperature $t1$ of the coolant which flows into the first jacket **22a** is also set higher (for example, 100°C.). Note that a broken line above the target wall temperature tw indicates a confidence limit of the coolant temperature.

In the low-load range, part of the coolant which flows through the first jacket **22a** flows into the first radiator passage **51** through the second radiator passage **52** (see G4). In detail, the coolant at the first target water temperature $t1$ flows in the first jacket **22a** through the CCV-side first coolant deriving passage **24**. Therefore, although depending on the situations, such as the ambient temperature and the wind velocity, the temperature inside the end part of the second radiator passage **52** provided with the thermally-actuated valve **54** normally becomes below the fully-open temperature to and above the fully-close temperature tc .

As a result, the thermally-actuated valve **54** is in a state where it is partially opened, and therefore, part of the coolant which flows through the first jacket **22a** flows into the second radiator passage **52**. Note that since the amount of coolant is small, its influence on the temperature of the entire coolant is small.

On the other hand, when the temperature of the coolant which flows through the first jacket **22a** becomes excessively high, the thermally-actuated valve **54** becomes fully opened. That is, when the temperature of the coolant which flows through the thermally-actuated valve **54** becomes above the fully-open temperature tc , the thermally-actuated valve **54** becomes fully opened. Most of the coolant which flows through the first jacket **22a** flows into the first radiator passage **51** through the second radiator passage **52**.

Therefore, the coolant is cooled. The temperature of the entire coolant is reduced. Therefore, it can suppress that the temperature of the coolant which circulates through the cooling system **2** becomes excessively high. Further, if the fully-open temperature tc and the first target water temperature $t1$ are set at substantially the same temperature, the temperature of the coolant which flows into the first jacket **22a** can be controlled more stably to the first target water temperature $t1$.

(Middle-Load Range)

In the first load **L1**, the amount of coolant which flows into the coolant control valve **4** (i.e., the amount of coolant

which flows into the first circuit **50**) reaches the upper limit (see G1). That is, above the first load **L1**, the water flow control cannot be performed. Thus, in the middle-load range, the cooling of the coolant is started. By gradually allowing the coolant which flows through the bypass passage **53** to flow into the first radiator passage **51** and cooling the coolant, the target wall temperature tw is held.

In detail, while holding the amount of coolant which flows into the first circuit **50** at the maximum, the coolant control valve **4** gradually reduces the amount of coolant which flows into the first passage **63**, and gradually increases the amount of coolant which flows into the second passage **64** (see G1, G2, G3, and G5). In the middle-load range, the coolant control valve **4** adjusts the temperature of the coolant which flows into the first jacket **22a** by adjusting the amount of coolant which flows through the second passage **64**.

At this time, the coolant control valve **4** controls the actuator **62** so that the rotary valve body **61** is located at the rotational position where the inflow opening **65** communicates with both the first passage **63** and the second passage **64**. Then, the opening between the inflow opening **65** and each of the first passage **63** and the second passage **64** is adjusted according to the load of the engine **1**.

Therefore, the temperature of the entire coolant which includes the coolant which flows into the first jacket **22a** decreases gradually (see G6, G7). Since the temperature of the coolant which flows through the first jacket **22a** decreases even when the amount of coolant is constant, the cooling quantity by the coolant which flows through the first jacket **22a** can be maintained. As a result, also in the middle-load range, the wall temperature of the combustion chamber **13** can be held at the target wall temperature tw (see G8).

In this cooling system **2**, in order to suppress the excessive temperature increase of the combustion chamber **13**, a second target water temperature $t2$ (for example, 88°C.) lower than the first target water temperature $t1$ is set as a target temperature of the coolant which flows into the first jacket **22a**. The water temperature control is performed until the temperature of the coolant which flows into the first jacket **22a** reaches the second target water temperature $t2$.

Thus, in this cooling system **2**, when the water flow control can be performed, the water temperature control is not performed. On the other hand, when the water flow control cannot be performed, the water temperature control is performed. In addition, the former (i.e., the temperature of the coolant which flows through the first jacket **22a** in the low-load range) is set higher than the latter (i.e., the temperature of the coolant which flows through the first jacket **22a** in the middle-load range) (see G6).

In the water temperature control, the coolant cooled by the radiator adjusts the heat exchanging quantity. On the other hand, in the water flow control, the heat exchanging quantity is adjusted by fluctuating the amount of coolant which circulates while bypassing the radiator. Therefore, the water flow control excels the water temperature control in the response and stability. The water flow control can stably control the water temperature even if it is set to a high temperature.

Further, in the water temperature control, the water temperature is lowered while maintaining the amount of coolant which flows through the first jacket **22a** at the maximum. Although the water temperature control is inferior to the water flow control in the response, since the heat exchange progresses comparatively quietly in the water temperature control, it can hold the combustion chamber wall temperature constant.

Thus, in this cooling system 2, it becomes possible to hold the wall temperature of the combustion chamber 13 constant at the high temperature within a wide load range of the engine 1, and the advanced combustion control, such as HCCI combustion, can be performed. Therefore, the engine 1 excellent in fuel efficiency can be realized.

In the middle-load range, the coolant which flows into the first radiator passage 51 through the second radiator passage 52 gradually decreases as the load of the engine 1 increases, and will no longer flow (see G4). In detail, the temperature of the coolant which flows into the second radiator passage 52 from the first jacket 22a decreases gradually from the first target water temperature t_1 . In connection with it, the temperature of the coolant which flows through the thermally-actuated valve 54 also decreases. The second target water temperature t_2 is lower than the fully-closed temperature t_c .

Therefore, in the middle-load range, the thermally-actuated valve 54 is gradually closed, and becomes fully closed. Therefore, the coolant which flows into the first radiator passage 51 through the second radiator passage 52 gradually decreases, and will no longer flow.

(High-Load Range)

In the high-load range, the conventional control based on the cooling of the coolant by the radiator 27 is performed. That is, in order to suppress the excessive temperature increase of the combustion chamber 13, the water temperature control for holding the temperature of the entire coolant, which flows into the water jacket 20 including the first jacket 22a, low is performed.

In detail, when the temperature of the coolant which flows into the first jacket 22a is cooled to the second target water temperature t_2 by the water temperature control in the middle-load range, it becomes in the high-load range. Then, in the high-load range, the coolant control valve 4 performs the water amount adjustment so that the temperature of the coolant which flows into the first jacket 22a is held at the second target water temperature t_2 . In order to lower the temperature of the entire coolant, the coolant control valve 4 adjusts the amount of coolant so that more coolant flows into the first radiator passage 51.

In detail, the actuator 62 is controlled, and the adjustment is made so that, as the load of the engine 1 increases, the opening between the inflow opening 65 and the second passage 64 becomes larger and the opening between the inflow opening 65 and the first passage 63 becomes smaller. Therefore, the coolant which flows into the first radiator passage 51 gradually increases, and the coolant which flows into the bypass passage 53 gradually decreases (see G3, G5).

Thus, the temperature of the coolant which flows into the first jacket 22a can be held at the second target water temperature t_2 , and the temperature of the entire coolant can also be held low (see G6, G7). Since the water temperature control and the control for holding at the second target water temperature t_2 are switched therebetween at a timing when the temperature of the coolant which flows into the first jacket 22a becomes the second target water temperature t_2 , the control can be switched smoothly for different contents of the coolant, and therefore, the continuity of the coolant control can be secured.

On the other hand, at this timing, since the target of the control is changed from the wall temperature of the combustion chamber 13 to the temperature of the coolant which flows into the first jacket 22a, degrees of change in the amount of coolant which flows into the bypass passage 53 from the coolant control valve 4, and the amount of coolant

which flows into the first radiator passage 51 from the coolant control valve 4 changes at this timing (see G3, G5).

In the high-load range, the wall temperature of the combustion chamber 13 also gradually increases as the load of the engine 1 gradually increases (see G8). However, since the temperature of the coolant which flows through the first jacket 22a is held at the second target water temperature t_2 , the excessive temperature increase can be suppressed.

Note that, in the high-load range, the thermally-actuated valve 54 is fully closed. The coolant does not flow into the second radiator passage 52. Note that, in the coolant control valve 4, the flow control may not be performed properly because the rotary valve body 61 is stuck. In such an abnormal state, the temperature of the coolant which flows through the first jacket 22a rises, and the combustion chamber 13 can become excessively high in the temperature (so-called "overheated").

On the other hand, in this cooling system 2, the second radiator passage 52 which bypasses the coolant control valve 4 and allows the coolant to flow into the first radiator passage 51 is provided. When the temperature of the coolant of the first jacket 22a exceeds the fully-closed temperature t_c , the thermally-actuated valve 54 opens automatically, and the coolant of the first jacket 22a flows into the first radiator passage 51 through the second radiator passage 52. Therefore, according to this cooling system 2, it can suppress that the engine 1 is overheated, even if the abnormality occurs in the coolant control valve 4.

Thus, according to this cooling system 2, the heat exchange (cooling) with the combustion chamber 13 by the coolant can be stably controlled with high response. As a result, the engine 1 can stably perform the advanced combustion control, such as HCCI combustion, and therefore, fuel efficiency can be improved. Even if the abnormality occurs in the coolant control valve 4, it can suppress the overheat of the engine 1.

<Modification of Cooling System>

FIG. 8 illustrates another cooling system 2' (a modification of the cooling system 2) of the engine. This cooling system 2' differs from the cooling system 2 described above in the flow control device.

That is, in the cooling system 2 described above, the coolant control valve 4 is illustrated as the flow control device. On the other hand, in this cooling system 2', the flow control device is comprised of two electromagnetic valves 71 and 72. Note that since other configurations are the same as the above embodiment, the same reference characters are used for the same configurations to omit their explanations.

In this cooling system 2', as simply illustrated in FIG. 8, instead of the CCV-side first coolant deriving passage 24, two outflow paths (a first outflow path 70a and a second outflow path 70b) which are branched from the first jacket 22a are formed inside the cylinder head 10H, at the outflow-side end part 10b of the engine body 10. The first outflow path 70a is connected to the bypass passage 53, and the second outflow path 70b is connected to the first radiator passage 51.

Further, the first electromagnetic valve 71 is installed at a connection part (it constitutes the first passage 63) between the first outflow path 70a and the bypass passage 53. The second electromagnetic valve 72 is installed at a connection part (it constitutes the second passage 64) between the second outflow path 70b and the first radiator passage 51. The first electromagnetic valve 71 opens and closes the first passage 63. The second electromagnetic valve 72 opens and closes the second passage 64.

This cooling system 2' adjusts the amount of coolant which flows through the first passage 63 and the second passage 64 by controlling the first electromagnetic valve 71 and the second electromagnetic valve 72, respectively. For example, like during "Low Temperature," when the coolant does not flow into both the bypass passage 53 and the first radiator passage 51, both the first electromagnetic valve 71 and the second electromagnetic valve 72 may be closed.

Further, like during "Full Warm-up," when the coolant flows into both the bypass passage 53 and the first radiator passage 51 and the amount of coolant is adjusted, the opening and closing timings of the first electromagnetic valve 71 and the second electromagnetic valve 72 may be adjusted according to the amount of coolant. For example, if a duty control is performed to repeatedly open and close the valves, the amount of coolant which flow into both the bypass passage 53 and the first radiator passage 51 can be adjusted accurately.

According to the cooling system 2' of the modification, since the flow control device is comprised of the two electromagnetic valves 71 and 72, the system configuration can be compact.

Note that the disclosed technique is not limited to the above embodiment, but also encompasses other various configurations.

For example, in the cooling systems 2 and 2' of the embodiment and the modification, the flow control device is disposed at the exit of the first jacket 22a. However, since the coolant circulates through the first circuit 50, the flow control device may also be disposed at parts other than the exit of the first jacket 22a. For example, the flow control device may be disposed near the suction port 3b of the water pump 3 so that the coolant flows into the flow control device from both the bypass passage 53 and the first radiator passage 51.

It should be understood that the embodiments herein are illustrative and not restrictive, since the scope of the invention is defined by the appended claims rather than by the description preceding them, and all changes that fall within metes and bounds of the claims, or equivalence of such metes and bounds thereof, are therefore intended to be embraced by the claims.

DESCRIPTION OF REFERENCE CHARACTERS

- 1 Engine
- 2 Cooling System
- 3 Water Pump
- 4 Coolant Control Valve (Flow Control Device)
- 10 Engine Body
- 10B Cylinder Block
- 10H Cylinder Head
- 13 Combustion Chamber
- 22a First Jacket (Water Jacket)
- 22b Second Jacket
- 27 Radiator (Heat Exchanger)
- 30 Second Circuit
- 31 Second Circulation Passage
- 40 Third Circuit
- 41 Third Circulation Passage
- 50 First Circuit
- 51 First Radiator Passage
- 52 Second Radiator Passage
- 53 Bypass Passage
- 54 Thermally-actuated Valve
- 60 Housing
- 61 Rotary Valve Body

- 62 Actuator
- 63 First Passage
- 64 Second Passage
- 65 Inflow Opening
- 5 S1 Inlet Water Temperature Sensor
- S2 In-jacket Water Temperature Sensor
- What is claimed is:
- 1. A cooling system for an engine, comprising:
a water jacket formed in a cylinder head of the engine and
through which coolant flows;
a heat exchanger that cools the coolant;
a bypass passage that bypasses the heat exchanger and
recirculates the coolant to the water jacket;
a first radiator passage that recirculates the coolant to the
water jacket via the heat exchanger;
a coolant control valve installed at a location where a
passage of the coolant branches into the bypass passage
and the first radiator passage;
a second radiator passage that bypasses the coolant
control valve and is connected to the first radiator passage;
and
a thermally-actuated valve installed in the second radiator
passage,
wherein the coolant control valve performs a water flow
control to adjust an amount of the coolant flowing into
the water jacket by adjusting an amount of the coolant
flowing through the bypass passage,
wherein the coolant flows into the first radiator passage
through the second radiator passage, when the ther-
mally-actuated valve opens,
wherein the coolant control valve performs a water tem-
perature control to adjust a temperature of the coolant
which flows into the water jacket by adjusting an
amount of the coolant flowing through the first radiator
passage,
wherein, during a first operating range, the coolant control
valve adjusts the amount of the coolant flowing into the
water jacket by flowing the coolant into the bypass
passage without the coolant flowing through the first
radiator passage and increasing the amount of coolant
flowing into the bypass passage until a maximum flow
rate as an engine load increases, and
wherein, during a second operating range, the coolant
control valve adjusts the temperature of the coolant
flowing into the water jacket by maintaining the
amount of the coolant at the maximum flow rate and
increasing the amount of the coolant flowing into the
first radiator passage while decreasing the amount of
the coolant flowing into the bypass passage, as the
engine load increases.
- 45 2. The cooling system of claim 1, wherein the coolant
control valve includes:
a housing provided with the bypass passage, the first
radiator passage, and an inflow opening through which
the coolant inflows;
- 50 55 a rotary valve body rotatably accommodated in the hous-
ing, intervening between the inflow opening and each
of the bypass passage and the first radiator passage, and
allowing the coolant that inflows through the inflow
opening to pass through a first water flow opening to
flow into the bypass passage and through a second
water flow opening to flow into the first radiator
passage; and
60 an actuator that rotates the rotary valve body,
65 wherein the amounts of the coolant flowing through the
bypass passage and the first radiator passage are
adjusted by controlling the actuator and changing open-

ings of the first water flow opening and the second water flow opening, respectively.

3. The cooling system of claim 2, wherein the temperature of the coolant flowing through the water jacket during the first operating range when the water flow control is performed and the water temperature control is not performed is set higher than the temperature of the coolant flowing through the water jacket during the second operating range when the water temperature control is performed and the water flow control is not performed. 5

4. The cooling system of claim 1, wherein the temperature of the coolant flowing through the water jacket during the first operating range when the water flow control is performed and the water temperature control is not performed is set higher than the temperature of the coolant flowing through the water jacket during the second operating range 15 when the water temperature control is performed and the water flow control is not performed. 10
